UNITED STATES PATENT OFFICE.

CASS L. KENNICOTT, OF CHICAGO HEIGHTS, ILLINOIS, ASSIGNOR TO THE KENNICOTT COMPANY, OF CHICAGO, ILLINOIS, A CORPORATION OF ILLINOIS.

TANK-CAR.

1,067,348.

Specification of Letters Patent.

Patented July 15, 1913.

Application filed January 22, 1912. Serial No. 672,524.

To all whom it may concern:

Be it known that I, CASS L. KENNICOTT, of Chicago Heights, in the county of Cook and State of Illinois, have invented certain 5 new and useful Improvements in Tank-Cars, of which the following is a specification.

My invention relates to railway rolling stock and has particular reference to a novel 10 construction of tank car.

Tank cars are at present employed for handling a variety of liquids and are frequently employed in handling hot liquids, that is to say, substances which harden at 15 normal temperatures but which melt or fuse at a temperature around the boiling point of water, for instance lard and similar substances. The practice in the handling of such substances is to allow the same to flow 20 into the tank while in hot or fluid condition. Shortly thereafter the material becomes set and to remove the same steam is injected into the tank by means of a series of pipes thus heating the material until it 25 becomes fluid when it may be removed. It will readily be seen that this involves a material change in temperature and will thus cause considerable expansion and contraction of the tank. The extreme expansion

30 may sometimes amount to as much as one inch for the entire length of the tank. It has heretofore been common to mount the tank on a rigid underframe, the tank resting on saddles and restrained from endwise 35 movement by means of head blocks at the ends of the tank. It is apparent that even though the tank and head blocks may be fitted nicely when the car is completed the expansion of the tank due to an extreme 40 temperature will tend to displace the head blocks and when the tank is cooled leave a space between the end of the tank and the blocks. As soon as the car goes on the road and is subjected to the shocks of buffing and

45 pulling, the tank will act as a battering ram and displace or destroy the blocks. Furthermore, such construction makes necessary the double riveting of the heads forming the ends of the tank to offset the blows 50 against the head block. I am aware that certain constructions have been patented with the idea of avoiding this difficulty, that is, fastening the tank to the underframe at its central portion by riveting or

by means of an interlocking connection. 55 This necessitates a strong and rigid underframe extending throughout the length of the car and is according to my theory an unnecessary weight and expense. I propose therefore to eliminate the underframe 60 entirely placing under each end of the car for a certain distance a shock resisting member, which member is riveted securely to the bottom plate of the tank, draft sills which are rigidly secured to the saddles or body 65 bolsters, then riveting or bolting the shock resisting member to the draft sills. This channel-shaped shock resisting member is in a sense a part of the tank and the heat will be transferred thereto causing expansion 70 and contraction with the tank. Any expansion of the tank as a whole will exert no strain with relation to the trucks inasmuch as the trucks will merely be placed farther apart under expansion and drawn 75 closer together under contraction.

The objects of my invention are therefore: 1st, to provide means for taking care of expansion and contraction without the necessity of employing head blocks and 80 double riveting the end plates, and 2nd, to eliminate the weight of a continuous underframe.

My invention will be more readily understood by reference to the accompanying 85 drawings, wherein,

Figure 1 is a side elevation of a tank car constructed in accordance with my invention; Fig. 2 is a bottom plan view thereof with the trucks and draft sills removed; 90 Fig. 3 is a transverse fragmentary section on a line contiguous to one of the body bolsters or saddles, and Fig. 4 is an enlarged fragmentary longitudinal section through the center of the car, the truck being eliminated. 95

Referring more particularly to the drawings it will be seen that a tank of ordinary construction is mounted upon trucks 10, there being interposed between the trucks 100 and the tank body bolsters or saddles 11. These saddles are preferably formed of two castings, the channels 12, forming the draft sills, separating the two castings as shown in Fig. 3. The castings and the draft sills are tied at the bottom by means of a plate 13, which plate carries the center plate 14 resting on a truck bolster 15. Secured to

the continuous bottom plate 16 of the tank at either end of the car is a channel 17, the flanges being turned downward and resting upon the flanges of the draft sills 12. These 5 channels 17 act as shock distributing members, the blows received by the draft sills being transferred to the plate 17, and by them distributed to the body of the car. In order to secure the two flanges together 10 I provide angles 18, which angles are riveted to the flanges of the channel 17 and riveted or bolted to the flanges of the channels 12. As shown in Figs. 1, 2 and 3, this channel 15 shaped member 17 fits the bottom plate 16 nicely and extends approximately a third of the length of the car. To one of the channels may be secured the air-brake mechanism 19, as shown in Fig. 1. The tank is held down by means of the usual 20 straps 20, anchored in the saddles and is provided with hand rail 21 and running boards 22. It will be seen that by this construction I provide for the condition of extreme 25 expansion and contraction of the tank without possibility of the shearing of any rivets and by the same means eliminate the cost and weight of a heavy underframe. While I have shown the channel-shaped- 30 shock-resisting members as extending a portion of the length of the car it will be apparent that variations may be made in this as well as other details, all without departing from the spirit of my invention.

I claim:

1. In a tank car, the combination of a 35 tank, trucks beneath each end of the tank, a channel-shaped shock-distributing plate secured to the tank at each end, and draft sills secured to said shock-distributing plates, substantially as described. 40
2. In a tank car, the combination of a tank, trucks beneath each end of the tank, a shock-distributing plate having downwardly extending flanges, said plates being secured to the lower face of the tank and 45 extending longitudinally thereof over a limited space at the ends of the car, and draft sills secured to said tank through the depending flanges of said shock-distributing plates, substantially as described. 50
3. In a tank car, the combination of a tank, trucks beneath each end of said tank, shock-distributing plates of channel shape the flanges thereof extending downwardly, each of said plates being of a length less 55 than one-half the length of the car, said plates being secured to said tank at the ends thereof, and draft sills secured to said tank through the medium of the flanges of said distributing plates, substantially as de- 60 scribed.

CASS L. KENNICOTT.
